UNITED STATES PATENT OFFICE.

CHARLIE SHARP, OF DIZNEY, KENTUCKY.

TRAIN CONTROL.

1,382,561.

Specification of Letters Patent. Patented June 21, 1921.

Application filed January 17, 1921. Serial No. 437,978.

To all whom it may concern:

Be it known that I, CHARLIE SHARP, a citizen of the United States, residing at Dizney, in the county of Harlan and State 5 of Kentucky, have invented new and useful Improvements in Train Controls, of which the following is a specification.

This invention relates to a train control apparatus, and wherein the occupied block 10 controls the track mechanism of remote blocks in advance of and at the rear of the occupied block, the invention residing in the construction, combination and arrangement of parts as claimed.

15 In the drawings forming part of this application like numerals of reference indicate similar parts in the several views, and wherein:—

Figure 1 is a top plan view.

20 Fig. 2 is an enlarged detail view in plan of the track mechanism and shoes.

Fig. 3 is a transverse sectional view.

Fig. 4 is an enlarged detail view of one of the shoes.

25 Fig. 5 is a view of the train carried mechanism.

Fig. 6 is a sectional view through the plunger.

Fig. 7 is a plan view of the mechanism 30 used in connection with a switch.

Referring to the drawings in detail, 10 indicates the rails of a trackway which are divided in the usual well-known manner, into blocks A, each block being equipped 35 with a track mechanism to be presently described. This mechanism comprises a motor 11 the armature shaft of which is indicated at 12, which shaft carries a pinion 13. Arranged in parallelism with the armature 40 shaft 12 is a shaft 14 which carries a large gear 15 and a drum 16. Connected to the drum is a cable 17 adapted to be wound about and unwound from the drum, which cable actuates the shoes 18 which are capable 45 of vertical movement and arranged adjacent the rails 10. These shoes are connected to a lever 19 by means of connecting rods 20, one of the rods being connected to the adjacent terminal of the lever at one side of 50 the pivot 21 thereof and the other connecting rod being associated with the lever at the opposite side of the pivot and at an appropriate point in the length of the lever.

The shaft 14 is mounted in a suitable bearing 14' illustrated. The electric motor 11

is connected in an electric circuit which is adapted to be closed by the wheels and axles of the train in a particular block, so that the occupied block controls the track mechanism of the remote blocks both in 60 front and at the rear of the occupied block. With each circuit, use is made of a wet battery 22, one of these batteries being arranged between every block as shown, the blocks being preferably one-half a mile 65 apart.

Now, assuming that there is a train occupying one of the blocks indicated at X in the drawings, the circuit is closed by the wheels and axles of the train in remote 70 blocks in advance and at the rear of the occupied block. For instance, the current from the battery 22 of the block X flows through the wire 23 forwardly in advance of the occupied block to energize the motor 75 11 of a block remote from the occupied block and in advance of the block. As the motor with which the wire 23 is connected operates, the pinion 13 meshing with the gear 15 rotates the shaft 14, thereby winding the cable 17 about the drum. The cable actuates the lever 19 which in turn moves the shoes 18 vertically from an inactive 80 to an active position. The current passes through the motor, flows through the wire 85 24 to the rail 10, following the rails to the train wheels, through the latter to the return rail 25, and from there back to the battery 22 in the block X. Leading from the battery in the adjacent block is a wire 26 which conveys the current from the battery 90 through the motor in the block at the rear of the occupied block, the circuit being completed in the same manner as that just described in connection with the block in advance of the train or occupied block. 95

The train carried mechanism includes a tripping block 30 which is supported by a vertical rod 31, the upper end of this rod being connected to one branch 32 of a bell 100 crank lever which is pivoted, as at 33. The opposite branch 34 of this lever engages a spring pressed sliding bolt 35 having one end normally disposed beneath the horizontally arranged lever 36 to support the latter 105 in this position. Suspended from the lever 36 is a spring 37. The lever is connected to the stem of the steam outlet valve 38. A rod 39 connects this valve lever 36 to the steam intake valve 40 so that the inlet and 110

outlet valves operate simultaneously in a manner to be hereinafter described. 41 indicates a cylinder communicating with the steam pipe and in this cylinder is arranged a spring pressed piston 42. The piston rod 43 is connected to the air control valve 44 which valve is operated with the steam valves above mentioned. In practice, when the shoes 18 are moved vertically in a manner above described from an active to an inactive position, they are arranged to obstruct the passage of the tripping block 30 of the train carrying mechanism. As the block 30 moves from one of the shoes the rod 31 is moved upwardly imparting movement to the bell crank lever, whereupon the branch 34 of this bell crank lever retracts the sliding bolt 35 against the tension of its spring. When the bolt 35 has retracted, the valve lever 36 is released and is pulled downwardly under the influence of the spring 37. As this lever is moved in this direction, the steam inlet valve 40 which is connected to the lever 36 by means of the rod 39 is closed. Simultaneous with the closing of this valve, the steam outlet valve 38 is opened permitting the escape of steam from the cylinder 41. With the escape of steam from the cylinder the piston 42 is moved toward one end of the cylinder during which time the air control valve 44 is opened by reason of its connection with the piston rod thereby applying the brakes to the train causing the latter to stop. A small chain 45 is connected at one end of a lever 47 associated with the steam intake valve, the opposite end of this chain being connected to the rod 48 which is used only by the firemen upon orders from the engineer or conductor of the train. The rod 48 is held in any adjusted position by the teeth 49 engaging the openings in a support 50 through which the rod is slidably mounted. This rod may be locked against movement in any suitable manner such as is indicated at 51, it being understood that the rod is only used upon special orders when it is necessary to bring one train close enough to another in an occupied block to assist the latter in moving over an incline or the like.

In Fig. 7 I have shown the track mechanism for use in connection with a switch or siding, wherein 60 indicates switch points,

the latter being connected by the bars 61, one of which is operatively connected to the switch stand 62. One of these switch points is connected with a V-shaped lever 63 through the instrumentality of a link 64, one branch of the lever 63 being disposed to engage the contact 65 to complete the circuit from one rail to the other through the wires 66 and 67 respectively, thus having the same effect upon the blocks of the track mechanism as a train would in an occupied block, the blocks 18 being in stopping position when the switch is arranged for the siding.

While it is believed that from the foregoing description the nature and advantages of the invention will be readily apparent, I desire to have it understood that I do not limit myself to what is herein shown and described and that such changes may be resorted to when desired as fall within the scope of what is claimed.

What I claim, is:—

1. In an automatic train stopping apparatus, the combination with the lines of rails of the trackway divided into blocks, and of mechanism located in each block and comprising a motor, a drum, driving connections between said motor and drum, shoes capable of vertical movement, a lever pivoted at a point between its ends, connecting rods associating the shoes with said lever, a connection between said lever and drum, and an electric circuit including said motor and a source of energy and adapted to be closed by the wheels and axles of a train in another block.

2. In an automatic train stopping apparatus, the combination with the lines of rails of the trackway divided into blocks, and of mechanism located in each block and comprising a motor, a drum, driving connections between said motor and drum, shoes capable of vertical movement, a lever pivoted at a point between its ends, connections between the lever and said shoes, a cable connecting the lever and drum, and adapted to be wound about and unwound from the latter, and an electric circuit including said motor and a source of energy and adapted to be closed by the wheels and axles of a train in another block.

In testimony whereof I affix my signature.

CHARLIE SHARP.
